Primary Examiner — L. A. Grabenstetter

(74) Attorney, Agent, or Firm — Leydig, Voit & Mayer, Ltd.

(57) **CLAIM**

The ornamental design for a safety frame for holding a tablet computer, as shown and described.

DESCRIPTION

1. Holder for electronic devices

1.1 : Perspective

1.2 : Front

1.3 : Back

1.4 : Right

1.5 : Left

1.6 : Bottom

1.7 : Top

Figure 1 is a perspective view of a safety frame for holding a tablet computer; Figure 2 is a front elevation view thereof; Figure 3 is a rear elevation view thereof; Figure 4 is a first side elevation view thereof; Figure 5 is a second side elevation view thereof; Figure 6 is a bottom plan view thereof; and Figure 7 is a top plan view thereof.

The broken lines, and surface bounded on all sides by broken lines, represent portions of the article that form no part of the claimed design.

1 Claim, 7 Drawing Sheets
